UNITED STATES PATENT OFFICE.

WILBERN S. BEEMAN, OF BATES CITY, MISSOURI.

SAFETY RAIL-COUPING DEVICE.

1,100,862.

Specification of Letters Patent. Patented June 23, 1914.

Application filed February 18, 1914. Serial No. 819,456.

To all whom it may concern:

Be it known that I, WILBERN SAMUEL BEEMAN, a citizen of the United States, residing at Bates City, in the county of Lafayette and State of Missouri, have invented certain new and useful Improvements in Safety Rail-Coupling Devices; and I do hereby declare the following to be a full, clear, and exact description of the invention, such as will enable others skilled in the art to which it appertains to make and use the same.

This invention relates to new and useful improvements in rail clamps, and has for its principal object the provision of a clamp which will prevent the rail from spreading, sinking, or creeping.

Another object of the invention is to provide a simple and effective means which may be easily and quickly put in position on a railroad rail without materially changing its construction.

A further object of the invention is to provide a rail clamp wherein the jaws will remain in the proper position until changed by the action of a person, preventing the clamp from becoming removed accidentally.

With the above and other objects in view, the invention consists in the novel combination and arrangement of parts which will be more fully set forth in the following specification and accompanying drawings, in which,

Figure 1 is a side view of a clamp constructed in accordance with this invention showing the same in position on a railroad rail, Fig. 2 is an enlarged detail sectional view of the clamp, and Fig. 3 is an end view of one of the clamp members to clearly illustrate the relation of the locking teeth.

Referring now to the drawings by characters of reference, the numeral 1 designates the outside clamp element which is used in conjunction with the inside clamp element, designated generally by the numeral 2. The outer clamp element comprises the main body portion 3 which is provided with the centrally located transversely extending aperture 4. This aperture 4 is preferably internally screw threaded as illustrated in Fig. 2 and is adapted to receive the end of the operating rod 5 by means of which the clamp is tightened. The body portion of the clamp has formed integrally therewith the head engaging element 6 which is adapted to lie beneath the head of the rail upon

which the device is used and keep the same from bending. A flange engaging member 7 is formed integrally with the body portion and extends transversely thereof as clearly illustrated in Fig. 2. This flange engaging extension 7 is provided along its free end with the teeth 8 which are adapted to coöperate with the opposite rail flange and lock the whole firmly in place.

The coöperating rail clamp 2 comprises the rail web engaging portion 9 which is provided with the flange engaging portion 10 having formed at its free end the teeth 11 which are adapted to coöperate with the teeth 8 for an obvious purpose. The bar 5 above referred to, is provided at one end with a right hand thread and at the opposite end with a left hand thread which are adapted to coöperate with the internally screw threaded aperture 4 to draw the clamp members 1 together. An enlarged portion 12 is formed on the bar intermediate its ends and is provided with the flat faces 13 to permit of the use of a wrench or similar tool for tightening the clamp members. Formed integrally with the bar near each end but spaced inwardly therefrom are provided the annular collars 14 which form the limit for the inward movement of the clamping element 2 when the device is in use.

It will be apparent from the foregoing, that in use the device is put in place on the rail with the outer clamping element removed. These elements are then slipped over the threaded end of the bar and said bar turned, thereby drawing the elements toward each other and firmly clamping the rail in place. Should it be desirable the ends of the bar may be extended and lock nuts placed in position thereon, thus preventing the devices from becoming loosened and causing any damage thereby.

While in the foregoing there has been shown and described the preferred embodiment of this invention it is to be understood that such changes may be made in the combination and arrangement of parts as will fall within the spirit and scope of the invention as claimed.

Having thus described my invention, I claim:

1. A device of the character described comprising a bar provided with an enlarged portion intermediate its ends, said enlarged portion being provided with squared faces to permit of the use of a wrench, the ends of the

bar being oppositely threaded, collars secured to the bar near its ends, but spaced inwardly therefrom, a pair of clamp elements adapted to be removably secured to the ends 5 of the bar, and teeth on each of said clamp elements to hold the same in proper position.

2. A device of the character described comprising a bar, a wrench engaging portion formed intermediate the ends of the bar, 10 collars secured to the bar near each end, the ends of the bar being threaded in opposite directions, a pair of rail clamps adapted to be removably secured to each end of the bar, one of said rail clamps abutting the collar, 15 and the other of said rail clamps being internally screw threaded and adapted to be drawn toward the first mentioned rail clamp to secure a rail between the clamps, and teeth on each of the clamps to hold the same in 20 proper relation when the device is in use.

3. In a device of the character described, the combination with a bar provided with oppositely threaded ends, collars formed integral with the bar and an enlarged portion intermediate the ends, of a clamp member 25 adapted to be secured to each end, said clamp members comprising two clamping elements, one of said clamping elements being internally screw threaded, the other of said clamping elements being adapted to 30 abut the collar, and teeth on each of the clamp members to hold the same in proper relation when the device is in use.

In testimony whereof, I affix my signature in presence of two witnesses.

WILBERN S. BEEMAN.
